(57) **CLAIM**

The ornamental design for a tire, as shown and described.

DESCRIPTION

FIG. 1 is a front, right-side perspective view of a tire of the design, with the pattern repeating uniformly around a circumference of the tire;

FIG. 2 is a front elevational view of the design of FIG. 1; FIG. 3 is a right-side elevational view of the design of FIG. 1, the left-side elevational view being a mirror image thereof; and, FIG. 4 is a close-up, fragmentary front elevational view of the design of FIG. 1.
